UNITED STATES PATENT OFFICE.

HERBERT W. LAWRENCE, OF MONTEVIDEO, MINNESOTA.

CURRY-COMB.

SPECIFICATION forming part of Letters Patent No. 390,484, dated October 2, 1883.

Application filed July 5, 1883. Serial No. 279,080. (No model.)

To all whom it may concern:

Be it known that I, HERBERT W. LAWRENCE, a citizen of the United States, residing at Montevideo, in the county of Chippewa and State of Minnesota, have invented certain new and useful Improvements in Curry-Combs, of which the following is a specification, reference being had therein to the accompanying drawings, in which—

10 Figure 1 represents a perspective view of my improved curry-comb complete; Fig. 2, a transverse vertical sectional view of the same, and Fig. 3 a detached sectional view of the comb proper.

15 The invention is designed to produce an improved curry-comb of simple construction, whereby the hair and dirt that collect in the teeth of the comb may be readily detached by a simple hand-pressure upon the handle by the 20 groom, the projecting portions of the teeth being by this operation drawn up out of the way, permitting the comb to be used as a "scrubber," as will be more fully hereinafter set forth. These objects I attain by the means 25 illustrated in the accompanying drawings, in which—

The letter A designates the back or frame of the comb proper, provided with the transverse toothed or serrated blades B upon its under 30 side (these blades being secured thereto or cast integral therewith) and upon its upper side with the arched handle C, this handle being provided at its ends with the laterally-projecting pins a and the projection b on its top.

35 The letter D designates a plate somewhat larger than the comb-frame A, and provided with transverse parallel slots for the passage of the blades B, this frame being held up normally against the under side of the said frame 40 A by means of a leaf-spring, E, secured to the under side of an arched handle, F, and bearing against the projection b and handle C. This arched handle F is larger than the handle C, fitting over it, as shown in Fig. 1, and is secured to or made integral with the plate D and provided at its ends with slots a', in which 45 work the guiding-pins a.

Secured to or formed integral with the plate D are the inclined cleaning flanges or scrapers 50 c c', which depend from the under side of the said plate and rest against opposite sides of

the blades B, near their serrated or toothed edges, these flanges being braced at their ends by a flange, d.

When pressure is exerted on the two handles by the hand of the operator, the toothed blades will be drawn up between the scrapers or flanges c c', the parts being guided in their vertical movements by means of the lateral pins a a. When the blades are drawn up out of the way in this manner, the flanges c c', impinging against the sides of the blades, will scrape off or dislodge all the dirt and hair that may be clinging to the teeth of same. By holding the blades up out of the way it will be observed that the scrapers c c' may be employed as scrubbers or "rubbers." It will also be observed that the scrapers c c', bearing against opposite sides of the blades, will greatly brace the same while they are being used.

It is evident that I may interpose a coil-spring between the two arched handles, in lieu of the leaf-spring shown, without departing from my invention. It is also obvious that the pins a a may be formed on the arched handle F and work in slots formed in the handle C instead of the manner shown.

Having thus fully described my invention, what I claim as new, and desire to secure by Letters Patent, is—

1. The combination, with the comb frame provided with toothed blades on its under side and an arched handle, C, on its upper side, of a scraper-plate, D, provided with depending scrapers adapted to bear against opposite sides 85 of the said toothed blades and an arched handle, F, larger than and fitted over the said handle C, and a spring interposed between the two handles, substantially as herein set forth.

2. The combination, with a comb frame provided on its lower side with serrated tooth-blades and on its upper side with a handle, of a spring-actuated slotted scraper-plate, D, provided with a handle and held normally up against the bottom of the comb-frame, the said tooth-blades projecting through the slots in the scraper-plates, and oppositely-inclined scrapers c c' upon the scraper-plate and adapted to bear upon opposite sides of the tooth-blades, whereby the tooth-blades may be withdrawn 95 and the scrapers employed as scrubbers, substantially as herein set forth.

3. The combination, with the comb-frame provided with an arched handle, C, and toothed blades B, the said handle being provided with pins *a a*, of a slotted scraper-plate, D, adapted 5 to bear up against the under side of the said comb-frame, this scraper-plate being provided with depending scrapers *c c'*, an arched handle, F, attached to the said scraper-plate and adapted to embrace or fit over the said handle C,

and a spring interposed between the two handles, substantially as described.

In testimony whereof I affix my signature in presence of two witnesses.

HERBERT W. LAWRENCE.
